CLAIM

The ornamental design for a vehicle fairing, as shown and described.

DESCRIPTION

FIG. 1 is a perspective view of a vehicle fairing, showing a first embodiment of our new design;

FIG. 2 is a front elevational view thereof;

FIG. 3 is a left side elevational view thereof;

FIG. 4 is a right side elevational view thereof;

FIG. 5 is a top plan view thereof; and

FIG. 6 is a bottom plan view thereof.

FIG. 7 is a perspective view of a vehicle fairing, showing a second embodiment of our new design;

FIG. 8 is a front elevational view thereof;

FIG. 9 is a right side elevational view thereof;

FIG. 10 is a left side elevational view thereof;

FIG. 11 is a top plan view thereof; and,

FIG. 12 is a bottom plan view thereof.

Stippling in the drawings represent the three-dimensional contours of the design, and is not intended to indicate

(Continued)

surface decoration. The broken lines shown in the drawings depict portions of the vehicle fairing that form no part of the claimed design.
